UNITED STATES PATENT OFFICE.

WILLIAM U. GRIFFITHS, OF PHILADELPHIA, PENNSYLVANIA.

AIR-COMPRESSING APPARATUS.

974,261.

Specification of Letters Patent.

Patented Nov. 1, 1910.

Application filed June 15, 1909. Serial No. 502,301.

To all whom it may concern:

Be it known that I, WILLIAM U. GRIFFITHS, a citizen of the United States, residing in the city and county of Philadelphia, 5 State of Pennsylvania, have invented certain new and useful Improvements in Air-Compressing Apparatus, of which the following is a specification.

My invention relates to improvements in 10 air compressing apparatus and it has for its object to simplify the construction of apparatus which is designed to compress and dispose of successive charges of air by the successive filling and emptying of a tank 15 with a suitable fluid, preferably air.

In addition to the simplifying of the construction, my invention also has for its object to provide means which is designed to prevent binding of any of the parts whereby 20 the apparatus may fail to operate.

Other objects and advantages of my invention will become apparent from the detailed description which follows.

A convenient embodiment of my invention is illustrated in the accompanying drawings, but it will be understood that various changes in the construction may be made within the scope of the claims without departing from the said invention.

30 In the drawings:—Figure 1 is a longitudinal sectional view of an apparatus provided with my invention some of the parts being shown in elevation; Fig. 2 is a transverse section on the line 2—2 of Fig. 1; and 35 Fig. 3 is a longitudinal section of the lower portion of the apparatus certain of the operative parts being in elevation and in different position from what is shown in Fig. 1.

Referring to the drawings: 1 designates a 40 tank, which may be of any desired shape, having an inlet pipe 2 through which water or a similar fluid enters the said tank and such water or other fluid is permitted to escape from the said tank through an outlet pipe 3. In my invention the operative parts are so constructed and arranged that the water enters the tank through the inlet pipe 2 only when the outlet pipe 3 is closed. The air which may be in the tank is compressed 45 as the water rises therein and is forced into a compressed air receiving chamber, not shown, through a pipe 4. The return of the air into the tank through the pipe 4 is prevented by means of a check valve at 5, the 50 construction of which is not shown. The outlet pipe 3 is adapted to be closed by a

valve 10 which is pivotally connected to a lever 11 pivoted at 12. The opposite end 13 of the said lever 11 supports a weight 14. The distance of the point of connection of 60 the said weight 14 to the end 13 of the lever 11 from the pivot 12 and its relation to the said pivot are such that the line of gravity of the lever and the weight may be moved to either side of the pivot 12 so as to retain 65 the valve 10 either in an opened or a closed position.

The inlet pipe 2 is opened and closed by means of a valve 15 which is provided with an operating rod 16 which projects through 70 an opening 17 in an ear or lug 18 projecting laterally from the weight 14. The turning or movement of the lever 11 about the pivot 12 occasions movement of the weight as indicated in Figs. 1 and 3 of the drawings. 75 Such movement occasions rotary movement of the valve 15 first in one direction and then in the opposite direction to open and close the same. Movement of the said valve in one direction is limited by reason of the 80 contact of the rod 16 with a stop pin 20 projecting from the end of the inlet pipe 2. Rotation of the valve of the inlet pipe occasions an inward and an outward movement thereof to open and close the same. The 85 opening 17 through the lug or ear 18 is considerably larger than the rod 16 so that there is considerable lost motion between the weight and the said rod. The valve 15 for controlling the flow of fluid through the 90 pipe 2 is so arranged that it is closed during the time that the valve 10 is open to permit the fluid to escape from the tank 1.

It is desirable that the opening and closing of the valves 10 and 15 shall be automatically effected and for this purpose I have provided a lever 25 pivoted at 26 upon a bracket 27. One end of the said lever is of frame-like or stirrup construction as indicated at 30 and a portion thereof is located 100 between the end portion 13 of the lever 11 and the projecting portion or arm 31, as clearly indicated in the drawings. By occasioning movement of the lever 25 about its pivot 26, movement of the lever 11 about its 105 pivot is also effected. By depressing the frame-like end portion 30 of the lever 25 it contacts with the end 13 of the lever 11 to depress the same and raise the valve 10 to open the pipe 3 and by reason of the engagement of the ear or lug 18 with the valve controlling rod 16 the latter is turned to the 110

left (referring to Fig. 1) to occasion an inward movement of the valve 15 to close the same. Upon raising or lifting the frame-like end 30 of the lever 25 it contacts with 5 the projecting portion or arm 31 and occasions movement of the lever 11, the weight 14 and the parts associated therewith to the positions indicated in Fig. 1. In the latter position the valve 15 is open to permit the 10 flow of water or other fluid into the tank 1.

For the purpose of automatically occasioning movement of the valve 25 and the parts operated and controlled thereby, I have provided a rod 40 which is connected to the 15 end portion 28 of the lever 25 which rod is adapted to be raised or lifted to raise or lift the end 28 of the lever 25 by means of a float 41. In order that the distance of the 20 points of connection of the rod 40 to the lever 25 may be varied as desired, I have provided a number of perforations in said lever as indicated at 42. The upper end of the rod 40 has movable connection with a yoke-like member 45 depending from a lever 25 on which a valve 47 is provided. The lever 46 is pivoted at 48 and the valve is located intermediate the said pivot and the said yoke-like member 45. The valve 47 is adapted to open and close an air inlet 50. When the operative parts are in the position 30 indicated by full lines in Fig. 1, the nut 51 by means of which connection is maintained between the rod 40 and the yoke-like member 45, is located a short distance above the 35 portion of the said yoke-like member through which the said rod projects and to which it is connected. This is for the purpose of allowing the said yoke-like member, together with the lever 46, to be lifted a 40 sufficient distance by the float 41 to open the valve 47 before the said yoke-like member comes into contact with the nut 51 to raise the rod 40.

The operation of the apparatus is as follows:—Assuming that there is no water or other fluid heavier than air in the tank and that the float 41 is at the bottom of its movement resting upon the stop shoulder 44 at the lower end of the rod 40, and that 45 the levers 11 and 25 and the parts associated therewith and controlled thereby are in the position shown in Fig. 1, the water or similar fluid will enter the tank through the inlet pipe 2, the valve 15 being open for that purpose, and lift the float 41 upwardly upon the rod 40 finally carrying it 50 into contact with the lower end or side of the member 45. As the float is raised, pressure of the compressed air thereon occasions an increase in the displacement of the 55 said float, that is to say increases the depth to which it extends in the fluid. It is also to be understood that this pressure increases as the expansive pressure of the air in the 60 tank which is being charged increases.

When the float has been carried to a sufficient height to raise the yoke or other member 45 and the lever 46 by which it is supported, the valve 47 is raised to open the air inlet and outlet 50 to release the pressure 70 of air in the top of the tank 1. The pressure of the air upon the float 41 being released, it bounds or moves rapidly upward and lifts the rod 40 occasioning movement of the lever 25 about its pivot and also occasioning pivotal movement of the lever 11 to carry the said levers together with the weight 14 and the parts associated therewith from the positions shown in Fig. 1 to the 75 positions shown in Fig. 3. The water in 80 the tank is then permitted to escape through the outlet pipe 3, the valve 15 being closed, the float 41 moving downwardly (as the water or other fluid escapes) on the rod 40 into contact with the shoulder 44 at the 85 lower end of the said rod. Its weight is sufficient when proper leverage is provided to depress the end 28 of the lever 25 and occasion movement of the levers 25 and 11, the weight 14 and the parts associated therewith, from the positions shown in Fig. 3 to that shown in Fig. 1. During the time that the water is escaping from the tank 1, air is entering the tank through the passage-way 50. The lever 46 and the valve 47 95 closing the passage-way 50 are held upwardly during this period by the upper end of the rod 40.

Having thus described my invention, I 100 claim:—

1. In an air compressing or charging apparatus, the combination of a tank, a passage-way into the said tank for the induction and eduction of air, means for opening and closing the said passage-way, a water inlet, a valve for opening and closing the said inlet, a water outlet, a valve for opening and closing the said outlet, a lever pivoted intermediate its ends and upon one 105 end of which the water outlet valve is supported and upon the other end of which a weight is carried, which weight has operative connection with the said water inlet valve, a lever pivoted intermediate its ends one end of which has operative connection 110 with the first-mentioned lever, a rod connecting the opposite end of the second-named lever to the means for opening and closing the said passage-way, and a float on the said rod, the said float occasioning movement of the said second-mentioned lever whereby the said first-mentioned lever and the weight carried thereby are actuated to cause the opening and closing of the water inlet and the water outlet valves. 115

2. In an air compressing or charging apparatus, the combination of a tank, a passage-way into the said tank for the induction and eduction of air, a valve for closing the said passage-way, a lever for supporting 120

the said valve, a water inlet, a valve for closing the said inlet, a water outlet, a lever pivoted intermediate its ends and having a valve upon one side of its pivot for closing 5 the said water outlet and having a weight upon the opposite side of the said pivot, the relation of the said weight to the said pivot being such that the line of gravity is moved from one side to the other of the said 10 pivot by movement of said lever, means extending laterally from the valve closing the water inlet, the said means having movable engagement with the said weight, a lever pivoted intermediate its ends and having 15 one end portion thereof in engagement with the water outlet valve lever, a rod having connection with the opposite end portion of

the said lever, and also with the lever supporting the valve for closing the passage-way for the induction and eduction of air, 20 a floating member on the said rod, the said member being moved upwardly upon the said rod by the filling of the said tank with water and being permitted to move downwardly upon the said rod upon the escape 25 of the water to occasion the opening and closing of the said valves.

In testimony that I claim the foregoing as my invention, I have hereunto signed my name this 14th day of June, A. D. 1909.

WILLIAM U. GRIFFITHS.
